UNITED STATES PATENT OFFICE.

STEPHEN J. MEEKER, OF NEWARK, NEW JERSEY.

DESIGN FOR A SHADE-ROLLER BRACKET.

SPECIFICATION forming part of Design No. 21,627, dated June 21, 1892.

Application filed January 25, 1892. Serial No. 419,221. Term of patent 7 years.

To all whom it may concern:

Be it known that I, STEPHEN J. MEEKER, a citizen of the United States, residing in Newark, in the county of Essex and State of New Jersey, have invented and produced a new and original Design for Shade-Roller Brackets, of which the following is a specification, reference being had to the accompanying drawings, forming a part thereof.

10 Referring to the drawings, Figure 1 represents a side view of a shade-roller bracket formed according to my design. Fig. 2 an end view, and Fig. 3 a perspective view, of the same.

15 The leading feature of my design consists in the scalloped outline presented when viewing the bracket from either the side, end, or in perspective. The sides of the shank portion *a* extend from a point about central of

20 its length in a curved line outwardly to a point *c*, where they meet with the outline of the feet *b b*, (which latter extend at right angles to the shank *a*.) and the outlines of the latter extend in a continuous curved line from

25 the point *c* in a circle, or nearly so, around the same to a point *d*, from which they turn or

curve outwardly from the line of the circle toward a central point between the feet and on the line of the shank portion *a*. The outline or edge of the latter at the point between the feet *b b* (represented at *e*) is made concave or curved inwardly from a straight line in order to form or complete, in combination with the curved or circular line formed from the points *d d*, between the feet *b b*, the scalloped outline or contour of the bracket when viewing the same from the side, as in Fig. 1, and in perspective, as in Fig. 3.

Having thus described my new and original design for brackets, what I claim, and desire to secure by Letters Patent, is—

The design for a shade-roller bracket, as herein shown and described, the same consisting of a shanked portion *a*, having the feet or ears *b b* extending in a line at right angles thereto, the whole having a scalloped outline formed by the curved lines between the points *a, b, c, d*, and *e*, as set forth.

STEPHEN J. MEEKER.
